UNITED STATES PATENT OFFICE

BERNARD DITISHEIM, OF PARIS, FRANCE

METHOD OF AND MEANS FOR TRANSFERRING HAIR AND FEATHERS FROM THEIR
NATURAL, TO ANOTHER SUPPORT

Application filed June 15, 1928, Serial No. 285,778, and in France June 27, 1927.

The invention relates to a method of and means for transferring hair and feathers from their natural to another support.

A process for the transfer of animal hair to fabrics or to any other supports, has been proposed in Patent No. 1,047,822 and formed a basis for the creation of an entirely novel industry. It was however difficult to carry out because after the separation of the fur from the skin, it happened that the hairs or feathers were not all on the same level, and that they were upright in places and flat in others.

The object of the present invention is to obtain products which are free from these irregularities.

The furs to be treated are stretched and secured to perfectly flat plates which are arranged vertically or practically vertically in freezing vats.

The introduction of these plates into the vats takes place so that the hairs or feathers rise regularly on contact with the liquid, instead of lying down. To that end, the introduction is effected in the direction opposite to that of the implantation of the hair or feathers.

The device for carrying into practical effect the process in question is illustrated by way of example in the accompanying drawings in which: Figure 1 shows in perspective a plate 1 provided with holes 2 so arranged as to enable skins of various shapes and dimensions to be stretched perfectly flat and to be sewn. Figure 2 is a longitudinal section of a vat 3; Figure 3 a cross-section; Figure 4 a plan. Figures 5, 6 and 7 show modified constructions of these vats.

The plates 1 which are introduced into the vat vertically are held in place therein by stops 4 arranged at the bottom of the vat, and by wedges arranged at 5.

In the case of several skins in one and the same vat, the furs facing each other, it becomes necessary to use a movable partition 6' (Figure 7) in order to ensure when taking out, the independence of the frozen blocks. These partitions are held in place by stops 4' and wedges 5', 5''.

Figures 5 and 6 show in cross-section and

in plan a modified construction for the arrangement and holding of the plates 1.

Instead of being placed against the walls of the vat, with the furs facing each other, the two plates are arranged against each other in the vertical median plane of the vat, the furs being arranged with their backs facing each other. The stops 4 and the wedges 5 are then done away with, the plates slide between lateral guides 6 or are held on the bottom of the vat by means of stops 4' and at the top by means of wedges such as those marked 5', 5''.

In the same way, a number of plates may be arranged in a vat varying according to the dimensions thereof, the furs being arranged face to face or in other directions.

The stops 4 or the lateral guides 6 may also be replaced by grooves provided in the walls of the vat.

The regular length of hair thus obtained is particularly valuable for the purpose of producing fur fabrics of large dimensions, the importance of which is very great. It is obvious that the utilization of fabrics made in accordance with this invention will be greatly facilitated if they are supplied to the trade in the usual dimensions of the ordinary fabrics, and without seams at the junction of the skins.

In such a case, the skins are cut so as to give them the exact shape of the plates, and congealed block of hairs obtained, after the removal of the skin by the usual process known from Patent No. 1,047,822, are juxtaposed so as to give the whole the desired dimensions. If necessary, this whole is frozen again for the purpose of combining its elements together.

A thin layer at the top of this collective block is thereupon thawed, dried by means of a wiping roller, whereupon a coating insoluble in water is applied to it by means of a second roller, this coating being intended to hold in one and the same film the root of the hairs or feathers, and the fabric constituting the support, which is put on after having been provided with the same coating. The fabric having been affixed, the passage

under a third roller acting as a press, ensures its perfect adhesion.

It is then merely necessary to proceed to the ordinary finishing operations: cleaning, drying, dyeing, lustering, etc. according to requirements.

By arranging under the fabric in a piece a succession of blocks joining each other, in a desired quantity, fur pieces are obtained, the width and the length of which are no longer limited to those of a plate, but have the same length and width as the most varied pieces of fabric.

The process which has been just described, is not limited to the use of water as agent for fixing the hairs or feathers in the block to be worked. It may be replaced, if desired, by any substance with a low point of fusion, such as fats, wax, paraffin etc. This substitution may be necessitated by the nature of the coating constituting glue for the new support.

The dimensions of the vats and frames may be any desired.

I claim:

- 25 1. A process for transferring hair or feathers from their natural skin to an artificial base which consists in securing the skins to plates and then introducing said skin carrying plates in a vertical position into congealing liquid containing vats.
- 30 2. A process for transferring hair or feathers from their natural skin to fabric which consists in securing the skins to perforated plates and then introducing said skin carrying plates vertically into vats containing congealing liquid said plates maintaining said skins in a uniformly flat condition.
- 35 3. Means for transferring hair or feathers from their natural skin to an artificial base, wherein the skins are secured to perforated plates, said plates having plane surfaces, said skin carrying plates being inserted into vats containing liquid, the hairs or feathers on the skins rising into a position vertical to the plate on contact with the liquid said plates being wedged against movement in the vat.
